By his Attorney

UNITED STATES PATENT OFFICE.

ROBERT F. METCALFE, OF BROOKLYN, NEW YORK, ASSIGNOR TO SOCONY BURNER CORPORATION, OF BROOKLYN, NEW YORK, A CORPORATION OF DELAWARE.

HEATING SYSTEM AND CONTROL THEREFOR.

Application filed May 14, 1925. Serial No. 30,312.

This invention pertains to heating systems, controls therefor, and elements and devices therein which cooperate to give complete and improved operation. It is well known that dwellings, office buildings, factories and certain manufacturing agencies, such as heat treatment furnaces, steam boilers and the like, are heated by the burning of liquid fuel. It is also well known that such heating, in most instances, is automatically controlled or governed by the amount of heat developed by the burning of the fuel. By reason of the automatic operation, it becomes highly advantageous to eliminate all fire hazards and other dangers and to provide against possible failures of the operating apparatus.

One of the objects of this invention is to provide an improved heating system that is fully automatic in operation and that provides safeguards against fire hazards, difficulties of operations and dangers which have heretofore been present in such systems.

Another object of the invention is to provide in a heating system an improved liquid fuel or oil burner of efficient operation constructed to automatically operate under normal predetermined control and to automatically cease operations when abnormal dangerous conditions exist in the boiler or furnace, in the fuel supply, in the burner itself or at other places in the system. The control also provides means for readily re-establishing automatic responsive operation after the burner has been stopped by reason of any abnormal condition.

A further object of the invention is to provide an improved heating system and a control therefor that have many novel features and that fully and satisfactorily meet all the former and more recent requirements of the National Board of Fire Underwriters.

Other objects and advantages will be more fully appreciated as a reading of the detailed description given below is had.

There is disclosed herein an improved heating system including an efficient automatic control, and this disclosure is considered as being preferred to other systems and their controls.

In the drawings forming part of this disclosure,

Fig. 1 is a diagrammatic view of a heating

system, an electrical control therefor and the various elements therein illustrated in diagrammatic form;

Fig. 2 is a sectional view of the flue of a furnace showing a flue control means;

Fig. 3 is an elevational view of a safety switch device responding to combustion conditions;

Fig. 4 is a sectional view taken on the line 4—4 of Fig. 3;

Fig. 5 is a sectional view taken on the line 5—5 of Fig. 3;

Fig. 6 is a sectional view taken on the line 6—6 of Fig. 7 of a fuel supply safety means; and

Fig. 7 is a view in section taken on the line 7—7 of Fig. 6.

While the disclosure herein is specific to one heating system and its control, it is to be understood that it is susceptible to some modifications and changes that are to be considered as being within the principles of this invention. Further, the heating system is such that different types of boilers or furnaces and fuel burners may be employed therein if desired. For satisfactorily disclosing the principles of this invention there is shown a furnace 1 of the ordinary hot water or steam type and an oil fuel burner 2 associated therewith in the usual manner. No specific constructions of a furnace and burner are herein illustrated as this heating system is considered as being adaptable for use with any satisfactory furnace and burner. However, a particular type of burner with which this system and its control has very satisfactorily operated is disclosed in my patent #1,491,156.

This preferred heating system includes the furnace 1, which in this instance is a steam boiler employed to heat a dwelling, office building, a chemical vat or the like. If desired the furnace 1 may be a heat treatment furnace or other manufacturing facility requiring heat. In this system the burner 2 operates to burn a liquid fuel or hydrocarbon such as oil. The system provides for automatic operation and in this instance there is provided a heat responsive means such as a thermostat 3 or a pyrometer which may be positioned at any desired place to govern the amount of heat delivered. The system is provided with an automatic control which

responds to the normal movements of the thermostat and thereby governs among other elements the normal operations of the burner 2. The control includes safety means which 5 protect against the operation of the system when abnormal conditions exist that would lead to dangers from fire, or explosions, or to destruction of property.

In this disclosure it is desired to specifically 10 describe the heating system, its operating elements or devices and its control as applied to the heating of a dwelling or home. While in such a disclosure there will be certain parts of the system that will be particularly 15 adapted to such an application of the system, it will be understood that when the system is employed for specific industrial or other purposes certain changes, substitutions or eliminations may be made, but there has been herein shown one way in which certain 20 regulating or controlling elements or devices may be employed and therefore the original conception is to be considered as being herein disclosed. As one example, there is herein shown a flue control which in this instance 25 constitutes a safety device to prevent damage in case of abnormal dangerous conditions in the furnace. When the heating system is employed for instance in a heat treatment furnace 30 in an industrial organization, such a control may not be required and in that event the safety control may be eliminated or shunted from operation. Again, certain of the safety or other operating means may not be required in industrial work, and such means 35 may be positioned to be responsive to other conditions of the specific operation.

In this heating system the burner 2 may be driven by any suitable means, and the control 40 for the operation of the burner may be of any suitable form which satisfactorily responds to the operation of the temperature responsive means or thermostat 3 and which has included therein satisfactory safety means 45 which respond when abnormal conditions of operation of the system are present.

The burner 2 herein is of the type which supplies air to form a combustible mixture with the oil fuel for burning. The normal 50 operation of this particular burner is to draw the oil to a nozzle by suction as by the passing of air over a definite opening in the fuel supply line. The combustible mixture may be ignited by any suitable means such for instance 55 as a spark-plug. This burner is preferably operated by an electrical motor 4 which is usually assembled on the burner base. It has been found convenient and satisfactory to control the operation of the burner and this 60 heating system by an improved electrical control means.

The control means includes among other elements the heat responsive means or thermostat 3, a safety switch 5 which is responsive 65 to abnormal conditions of fuel feed, a safety

switch 6 mounted in the furnace and responsive to the various abnormal conditions thereof such as high steam pressure, a flue control safety means 7 which responds to abnormal heat in the gases passing from the furnace through its flue 8, and a further safety means in the form of a switch 9, considered here as a "flapper switch" and which is operated by reason of combustion or non-combustion of the mixture. The thermostat 3 functions to normally control the operation of the burner to cause in this instance its intermittent burning, and the safety means herein before outlined operate to prevent normal operation of the burner in the event abnormal 70 conditions exist in the heating system.

It is desired to provide such satisfactory safety and operating elements in this heating system as will prevent the existence of fire hazards, danger of explosion and danger 85 when opening electrical circuits which often create relatively long sparks between the switch points as they are separated. The safety means above noted assist in preventing operation when there is a possibility of such dangers and the circuit to the burner motor 4 is provided with an enclosed switch 10 which eliminates dangers from sparks at the switch points.

The source of electrical power for operating 90 the burner motor and the electrical control is derived from power lines 11 and 12 of the ordinary house lighting circuit which is usually of 110 volts potential. A suitable switch 95 preferably in the form of a snap switch 14 is employed to connect the burner apparatus and its control with the power lines 11 and 12, and a suitable connection board 15 is mounted in a convenient place on the burner for carrying 100 the main binding posts 16 and 17. Any desired type of motor 4 for driving the burner 105 may be employed, but the motor preferred is one of the closed armature type provided with a field 18 which is connected to post 16 by line 19 through enclosed switch 10, and line 110 20 while the other end of the field is connected to binding post 17 through line 21. When the switch 10 has been closed the motor will drive a suitable blower fan which delivers air to the burner for mixing with the oil to form 115 the combustible mixture.

In the electrical circuit for the spark-plug a line 22 leads from the line 20 to a primary transformer winding 24 and back to binding post 17 by line 25. The spark-plug is connected through a secondary winding 26 to ground. This ignition coil or transformer is provided with a core 27 which has a winding 28 wound thereon and connected by line 29 to contact point 30 which is normally in 120 engagement with contact 31. This contact 31 is carried by an arm 32 adapted to be oscillated by the magnetic intensity of core 27 thus causing a spark to jump across the contacts of the spark-plug in the usual manner. 125

This may be more clearly appreciated when it is understood that coil 28 acts as a secondary winding for coil 24 and gives about 15 volts across contacts 30, 31. As the flux in core 27 builds up due to the ampere turns in coil 28, arm 32 will be drawn down and contacts 30, 31 will be open thus opening the circuit through the secondary coil 28 and causing a high electro-motive force to be instantly induced in coil 26 and carried to the spark-plug where it will jump from one contact to the other and from there to ground thus operating the spark-plug. The arm 32 is electrically connected by a line 34 to a contact 35 which normally closes against a contact 36 carried by switch 9. The contact 36 is connected with the other end of the coil 28 by line 37. The preferred construction of contacts 35 and 36 may be noted in Fig. 4 and the details thereof will be more fully described later. It will now be seen from the connections above outlined that when the burner motor switch 10 is closed the motor 4 will rotate driving the fan for the air, and the spark-plug will produce a spark for the ignition of the combustible mixture. The spark may or may not be continued during combustion. It is preferred in this instance to discontinue the spark while actual combustion conditions exist in the burner 2 and therefore the movement of switch 9 separates the contacts 35 and 36 thereby opening the circuit which causes the operation of the spark-plug.

The control for this heating system may be operated in any desired manner that permits response to the thermostat 3 and to the safety means and to the presence or absence of combustion, so that in case of abnormal conditions in the system or the failure of ignition at the start of the burner or of the cessation of combustion during the running or by reason of the fuel supply becoming exhausted or of such nature as will give explosive mixtures, the system and particularly the burner will be stopped from further operations, thereby eliminating danger to human life and property and to the particular apparatus in this heating system.

It is preferred in this control to provide a suitable master control means which is changed due to various electrical connections and to provide other mechanically operating means for operating with the master control for controlling the operation of the burner in response to the normal operation by reason of movements of thermostat 3 or by reason of the operation of the various safety devices. In this instance, there is provided an electro-magnetic device which forms part of the master control. This device is characterized by its capability of being substantially magnetically balanced to prevent movement and to be magnetically unbalanced to create movement thereof. A device of this nature and a device which is preferred to be used comprises a suitable control motor 38, usually of the repulsion type. This motor is provided with a field winding 39 connected to binding posts 16 and 17 by lines 40 and 41 respectively. This field winding is closed across the supply circuit during all of the operation of the heating system, i. e., during the time snap switch 14 is "on". This control motor is provided with brushes 42, 44 and 45 on its commutator. Preferably, brush 42 is connected to the ground. By reason of the characteristics of motors of this character, when there is a circuit closed between brushes 42 and 44, there will be rotation of the motor. Thus the motor will be considered as being magnetically unbalanced. When there is a circuit closed only between brushes 42 and 45, there will also be rotation of the motor, and thus the motor will be considered as being magnetically unbalanced. If, however, there is a circuit through brushes 42 and 44 and a circuit through brushes 42 and 45, the motor then becomes substantially magnetically balanced and its rotation ceases. The stopping of the motor when the two circuits are closed is due to the fact that each of the single circuits endeavors to cause the motor to rotate in opposite direction.

With this repulsion control motor, it is noted that the circuits which extend from the brushes are of a voltage considerably less than the 110 volts impressed across supply lines 11 and 12. Thus the control part of the heating system will be operated on a low voltage. The low voltage usually approximates 10 volts.

The control motor 38 is adapted to drive mechanically a distributor 46, and there is herein shown diagrammatically a suitable shaft 47 for the drive. It will be understood that any desired gearing may be employed between the motor and the distributor so that the proper speed of rotation of a distributor arm 48 will be possible. Mounted on this shaft 47 is a suitable cam 49 which operates on a rocker arm 50 against extension 51, thereby causing its other extension 52 which carries the burner motor switch 10 to move to open or close the contacts in the switch 10. It is usual in this enclosed type of switch to have a quantity of mercury which moves to close the circuit between the two switch points.

The distributor may be of any desired construction or formation so long as it provides a suitable number of contact segments which are adapted to be wiped by a contact arm moved by the control motor. In this construction, it is preferred to have the contact segments of annular construction and to have them mounted concentrically, so that the arm 48 pivoted on shaft 47 may wipe over the segments during its movement by the rotation of the control motor. In such a con-

- struction, there is herein provided segment 54 which is in length about 320 degrees of a circle. Mounted concentrically with segment 54 is segment 55, which is about 300 degrees of a circle in length. It is desirable to have the segment 54 longer than the segment 55, so that, under normal operating conditions of this heating system, the arm 48 will engage only the segment 54 when the burner 2 is normally stopped. This position of arm 48 is considered to be the starting position of the operation of this heating system. It is to be understood that while there is approximately 20 degrees difference in length between the two segments, this difference may vary considerably or there may be some means of raising a contact 56 carried by the arm 48 from the segment 55 while at the same time allowing a contact 57 carried by the arm to engage segment 54. The main purpose is that, in normal stop condition of the burner, the contact 57 will be in engagement with segment 54 and the contact 56 shall be out of engagement with segment 55.
- This distributor also provides for a segment 58 which may be suitably positioned to receive the distributor arm 48. In this instance, segment 58 is shown as being positioned between the ends of segment 54, so that contact 57 will engage segment 58 under certain conditions of operation, later to be described in full. This segment is positioned so that contact 57 would engage therewith. It is, however, quite immaterial as to which of the contacts carried by the arm 48 engages segment 58 so long as an electrical circuit may be established to cause the control motor to rotate. This segment 58 usually is termed a safety stop segment, and when the distributor arm 48 engages the same, it is considered that the arm is in a safety stop position. When the arm 48 so engages segment 58, the burner has been stopped by reason of the existence of some abnormal condition in the heating system. Under such circumstances, it is desirable to be able readily to return the control system back to its normal responsive position. It is herein provided that some additional operation shall be completed in order to accomplish this end. This additional operation may be performed manually or may be accomplished by some automatic or remote control. However, for the purpose herein disclosed, there is provided a suitable push button 59 which closes a circuit through the motor 38 and the distributor, causing the motor to rotate, moving the arm 48 to its normal position in engagement with segment 54 alone.
- From the description thus far, it will be seen that there is a master control for the burner which includes the electro-magnet device adapted to be magnetically balanced and unbalanced, such as the control motor 38, a distributor mechanism 46 comprising the seg-
- ments 54, 55 and 58, and the distributor arm 48 and the main normal control in the form of the thermostat 3.
- In the complete heating system, the furnace employed, as hereinbefore noted, may be a boiler, hot air or other desirable type of furnace. In the event excessive heat is developed, the furnace itself will absorb only a certain amount, and thereafter developed heat will mostly pass through the flue to the atmosphere. In furnaces which are of the hot water or steam type, the heat developed will normally be absorbed by the water, and should this water become exhausted the heat will then bring the furnace to its heat saturation point and the heat thereafter developed will pass to and through the flue. It is well understood in the heating art that the boiler sections crack and are ruined by reason of low water conditions and thus cause excessive repair expense. The heating system herein disclosed prevents operation of the apparatus when the furnace or boiler has abnormal conditions existing therein. Normally, a boiler will absorb the heat, and the hot water or steam will be conducted away from the boiler. Should anything happen to prevent such conduction of the heat, then excessive steam is developed, and in that instance the safety means 6 operates to open a circuit to the control motor and stop the burner, or prevent the starting of the burner.
- If the heat developed becomes excessive in the flue, the safety means 7, which may be of any suitable form, will operate to open the circuit. In this instance, the fusible link employed will melt and open the electrical supply line. In order to provide some means for indicating whether this fusible link is melted or not, there is provided an indicating or pilot lamp 60 connected across the lines 11 and 12. In order to test whether link 7 is melted, snap switch 14 is turned on and by reason of current being drawn due to the fact that field 39 of the control motor is closed, the pilot lamp 110 will light to indicate that the fuse has not been melted. If the indicating lamp 60 remains dark, then a new link will be required to be placed in the flue. While there is herein described a specific type of flue control means, it is to be understood that other satisfactory means for accomplishing the same result may be employed. It is to be noted that when the flue control safety means has operated or been melted, the electrical supplies to the burner motor and to the electrical control will both be opened so that further operations of the burner itself or control therefor will be prevented.
- It is desirable to provide the furnace safety means 6 in such form as to be responsive to steam pressures, for when this heating system, as heretofore noted, is installed in dwellings and the thermostat 3 located in one of the rooms, it will be seen that in the morning 120

high steam pressures would be developed in the furnace before thermostat 3 would become responsive to stop the burner. When the steam in the furnace reaches a predetermined pressure, the safety means 6 operates to open a circuit to the control motor, thereby causing the burner to cease operations.

This heating system includes a suitable safety means responsive to abnormal conditions of the feeding of the fuel to prevent operation of the burning apparatus when there are dangers of fires and explosions. Any particular safety means may be employed for this purpose. It is found, however, that in the oil burning type of heating system, it is desirable to provide a safety means which operates when the level of the oil varies a predetermined amount from its normal. In the present system there is provided electrically connected in series with the thermostat 3 a contact 61 positioned to engage contact 62 to maintain the circuit closed under normal conditions of fuel feed. A float 64 is provided with a stem 65 which engages an arm 66. Stops 67 and 68 are placed on the stem 65 and permit predetermined movements of the float 64 without moving the arm 66. In the event the level of the fuel drops below a predetermined point, stop 67 engages arm 66 and the downward pull on the right-hand end of arm 66 opens contacts 61 and 62, thereby opening the control circuit and preventing operation of the burner; or, if the burner is in operating condition, to cause the same to be stopped. In the event the fuel level is too high, stop 68 engages arm 66, and the upward push on arm 66 raises the same, thereby separating contacts 61 and 62, creating the same safety operations as under the conditions of low level.

One of the main purposes of this safety means 5 is to prevent the operation of the burner when the fuel level is so low as to preclude the supplying of a sufficient quantity of oil, for it is recognized that when a too small quantity of oil is mixed with predetermined quantities of air, an explosive mixture results. This particular safety means prevents operation of the burner under such conditions. When the oil level is too high, which would permit the oil to leak from its chamber to the basement floor, it would be dangerous to start the fuel burner, and thus the safety means 5 prevents the operation of the burner under such conditions, or, if the burner is running, stops it, thereby eliminating fire hazards. While this type of safety means 5 is shown in diagrammatic form in Fig. 1, the preferred mechanical construction thereof is illustrated in Figs. 6 and 7, and will be more fully described hereinafter.

It has been stated that the thermostat 3 operates to govern the main control under normal conditions of operation of the heating system. Various types of thermostat

may be employed for this purpose. One of the main difficulties with thermostats is the "fluttering" which takes place and thus prevents the completion of operation. In this disclosure there is provided a main moving contact member 69 of the thermostat which carries a magnetically influenced element 70 and an electrical contact 71. Positioned near the movable member 69 is a core 72, which is magnetized by coil 74 provided in line 75. The other end of the coil is connected to contact point 76. In the operation of this thermostat, the movable member 69 moves to the left by reason of its expansion characteristics, permitting contacts 71 and 76 to engage, thereby closing the circuit and creating magnetic force in member 72 which, acting on element 70, pulls the member 69 over and maintains it in that condition, resulting in firm engagement of contacts 71 and 76. This condition will continue until the thermostat operates by reason of heat developed to open the contacts. The thermostat herein shown is to be considered as a two-point thermostat.

The operation of this heating system and the burning apparatus included therein is as follows under normal conditions when it is assumed that the fuel feed safety means 5 and the boiler safety means 6 are in normal closed condition. The distributor arm 48 is assumed to be in its normal position in contact with only segment 54. By reason of lack of heat, the thermostat member 69 will move to close contacts 71 and 76, thereby closing an electrical control circuit as follows: from ground to distributor arm 48, to segment 54, to thermostat member 69 by line 77, through coil 74 and line 75, switch contacts 61 and 62, line 78 through relay 79, line 80 through safety means 6, line 81 to brush 44, through the armature of control motor 38 and brush 42 to ground. This gives one circuit through the control motor and will cause rotation thereof. In the movement of the motor, shaft 47 will be rotated, causing switch 10 to be closed by reason of the movement of rocker arm 50, and the distributor arm 48 will be mechanically driven so that it wipes across segments 54 and 55. As heretofore noted, the spark-plug will be placed in operation as soon as switch 10 closes. Contacts 35 and 36 in the spark-plug circuit will be closed due to the fact that there is no combustion taking place in the burner. The control motor 38 normally continues to rotate until combustion takes place unless there is no fuel when it will stop for arm 48 has reached safety stop segment 58. The distributor arm has a permissible travel from the time it simultaneously engages segments 54 and 55 until it should pass onto segment 58. The lengths of segments 54 and 55 are such that combustion will take place before distributor arm reaches the point where it passes from segments 54 and 55, unless there is some unusual difficulty. It

will be seen that the distributor arm may stop at any point along its permissible travel due to combustion taking place. Instantly upon the lighting of the combustible mixture 5 or the initiation of combustion, the pressure derived therefrom causes switch 9 to be moved, overcoming the resistance of an adjustable weight 82. By reason of this movement of switch 9, contacts 35 and 36 to the 10 spark-plug are separated and contacts 84 and 85 of another circuit are brought into engagement. When the circuit which includes the thermostat is completed across brushes 42 and 44, causing rotation of the control motor 15 38, the relay 79 draws pivoted arm 86 upward, opening contacts 87 and 88. There is then no closed circuit from segment 55 to brush 45 of the control motor, and the motor will operate and continue to operate due to 20 the closed circuit across brushes 42 and 44. The relay 79 acts to separate contacts 87 and 88 before the distributor arm engages segment 55.

With the closing of contacts 84 and 85 due 25 to combustion taking place, a second circuit to the control motor is completed as follows: from ground to contacts 85 and 84, through the flapper switch, line 89, line 90 to brush 45 on control motor 38, thus there is established a second circuit through the control 30 motor; and by reason of the position of brush 45 in respect to brushes 44 and 42, and by reason of the windings of the field and armature of this control motor, it is required 35 to stop rotation, as the circuit through brushes 42 and 44 endeavors to rotate the armature in one direction and the circuit through the brushes 42 and 45 endeavors to cause the armature to rotate in the opposite 40 direction. When both of these circuits are closed, there is a substantial magnetically balanced condition existing in the motor, and it ceases to rotate. The burner now is operating to burn the combustible mixture, and it 45 will so continue under normal conditions of operation until the thermostat 3 opens, thereby separating contacts 71 and 76 and opening the circuit across brushes 42 and 44. The opening of this first circuit leaves the second 50 circuit through brushes 42 and 45 predominant, and the control motor is caused to rotate in the opposite direction, moving the distributor arm 48 in counter clockwise direction back to its normal position in engagement with only segment 54 and in position to 55 start up again. The opening of the first circuit causes relay 79 to release arm 86, thereby permitting contacts 87 and 88 to engage, thus creating a semi-substitute circuit for the 60 second circuit, which causes the counter clockwise movement of arm 48 back to normal condition, for the first circuit through segment 54 has been opened, and due to cessation of combustion, switch 9 is moved by weight 82 65 back to normal "hang" position.

In the event of failure of ignition in the burner at the beginning, the flapper switch 9 would not be moved, as there would be no pressures resulting from combustion. Therefore, the first circuit across brushes 42 70 and 44 of the control motor would continue and cause the motor to continue rotation, moving the distributor arm 48 onto safety stop segment 58 where all circuits to the control motor would be opened. At the same 75 time, the motor switch 10 to the burner motor would be opened and consequently all operations of the burner apparatus would be stopped. By pressing the push button 59, a circuit is created from ground, control motor 80 brush 42, armature of control motor 38, brush 44, line 94, push button 59, line 95, segment 58, and distributor arm 48 to ground, thereby causing the control motor to rotate, moving the distributor arm onto segment 54, thus 85 placing the apparatus back into normal responsive condition; that is, responsive to the operation of the thermostat.

In the event ignition takes place at the beginning and there is later a failure of combustion for any reason, the flapper switch by reason of the weight 82 would move to its normal "hang" position separating the contacts 84 and 85, leaving the first circuit closed through brushes 42 and 44, and the control 90 motor 38 would thereby rotate as the second circuit would be open, and distributor arm 48 would be moved onto safety stop segment 58 or into safety stop position, stopping the 95 operations of the apparatus as before described. It will be noticed that the flapper switch is instantly responsive to the pressures of combustion. It will be seen that, since the flapper switch is responsive to combustion conditions, in the event there is a cessation 100 of combustion there is instantly a change in the control system which immediately leads to the stopping of the burning apparatus.

Referring now to the other safety means, 110 it will be noted that it is preferred to have the thermostat 3, the fuel feed safety means 5 and the boiler safety means 6 all connected in series in the first circuit through the brushes 42 and 44 of the control motor, and that the 115 second circuit includes the flapper switch which is responsive to the conditions of combustion and that the closing of both of the circuits causes the motor to stop rotation. It will also be noted that if both of these 120 circuits are open the motor will not rotate. Further, it will be noted that when the motor is stopped by reason of the closure of both circuits that there may be a selective unbalancing of the motor, that is, the unbalancing will 125 cause the motor to rotate clockwise or counter clockwise. The unbalancing may result from abnormal conditions of combustion, fuel feed or furnace conditions. The unbalancing will also result from the opening of the thermo- 130

stat. In addition, the safety device in the flue may operate to stop all operation of the heating system. Each of the various safety means is responsive separately and acts separately to stop the apparatus. It is recognized, however, that the safety means act through the control motor 38. But each particular safety means is independent of any other safety means and it functions to automatically and independently stop the operations of the burning apparatus. It is also to be noted that the operation of any of the safety means changes the electrical connections in the control.

Referring now to Figs. 3, 4 and 5 a particular type of flapper switch is herein disclosed. A part of the frame 95 of the burner 2 is provided with an opening 96 in which there is placed a suitable plate 97 usually pivoted at 98. This plate 97 is so constructed that it substantially and practically fills the opening 96. The plate carries the contact 35 of the spark-plug circuit. A ring 99 is affixed to the part 95 and pivotally carries a frame 100 which is provided with a projection 101 carrying a roller 102 which in turn normally engages the plate 97. When combustion takes place the pressures developed by combustion cause the plate 97 to be pivoted about its pivot point 98 to press against the roller 102 causing frame 100 to oscillate to the left. This frame 100 carries the weight 82 which is adjustable on the screw threaded rod 104 so that the response to the movement of plate 97 may be varied if desired. The ring 99 carries an arm 105 of electrically conducting material which is adapted to be engaged by contact 84 carried by the frame 100. The extreme free end of the electrical conducting arm 105 forms contact 85. It will be seen that when combustion takes place, contacts 84 and 85 will be closed and create the closing of the second circuit as above defined. The frame 100 is adapted to carry contact 36 at its lower end. While contacts 35 and 36 are illustrated as being mounted in definite positions they may be mounted in any particular desired manner. There is, however, a certain advantage in their present locations in that when the frame 100 and the plate 97 oscillate back to their normal positions contacts 35 and 36 will be brought together with a definite pressure as both frame 100 and plate 97 oscillate about definite pivot points. Suitable electrical flexible conductors are shown as being connected to the various contacts with this type of flapper switch construction. These conductors may be varied as desired respecting their forms and locations.

The preferred construction of this switch as herein illustrated functions to be instantaneously responsive to the beginning of combustion and to the cessation of combustion.

Referring now to Figs. 6 and 7 the preferred feed fuel safety means will be de-

scribed in detail. This means is diagrammatically shown on the burner 2 in Fig. 1 and the frame 106 thereof constitutes a chamber for receiving fuel in the form of oil to a normal level illustrated by the line 107. The fuel preferably enters the safety means by pipe 108, passes through valve passage 109 to the chamber formed in frame 106 and passes therefrom through pipe line 110. A suitable float 111 and the usual operating means responsive to the position of the float 111 vary the setting of valve rod 112 at its seat of the valve passage 109. The float 64 is shown to the left of float 111 and is adapted to move in accordance with the position of the level of the fuel. This float 64 carries shaft 114 which is guided by its lower end by a suitable frame 115 and at its top end it carries a plate 116. This plate is provided with a slot 117 and with arms 118 and 119 which are respectively adapted to engage stops 68' and 67'. The switch 5 is provided with contacts 61 and 62 and mercury in reservoir 120 operates to close and open switch 5. The mercury reservoir comprises an elongated tube 120 having a recessed portion 120' in one end thereof, as shown more clearly in Fig. 6. Mercury contacts 61 and 62 extend within the tube 120 and are so positioned that when the tube is tilted to the left, as shown in Fig. 6, mercury covers both of the contacts 61 and 62, forming a closed electric circuit. Current then flows through conductors 78 and 78' to contact terminal 61, from terminal 61 through the mercury to contact terminal 62, from terminal 62 through conductors 75' and 75, completing the electrical circuit through the remaining conductors and devices heretofore described. When the mercury tube tilts to the right, the mercury flows away from contact terminal 61, breaking the electric circuit. This opening and closing is completed within the completely closed wall of the switch thereby eliminating fire hazards.

It will be noted that when the level of the fuel rises that projection 118 engages stop 68' and moves the switch 5 to its open position. When the level of the fuel lowers, float 64 will drop causing extension 119 to engage stop 67' thereby moving the switch 5 to its open position. The construction of this particular type of safety means is simple and permits satisfactory normal operation but prevents the operations of the burner when abnormal fuel feed conditions exist. A satisfactory means for cleaning the fuel feed chamber is provided by suitable plugs 121 and 122.

From the foregoing complete description it will be noted that there is herein disclosed an improved heating system having its burning apparatus operative in a very efficient manner under normal conditions, and that when abnormal conditions exist in the system

suitable safety means are provided for instantaneously perfecting changes which stop the operations of the burner. Suitable modifications and changes may be made in the 5 heating system and its control and its devices and its operating elements as desired, but it is to be understood that such changes and modifications are considered to be within the scope and principles of this invention as outlined in the following claims.

What I claim is:—

1. In an oil burning apparatus, the combination of means for feeding, igniting and burning oil fuel; a master control for governing 15 said feeding, igniting and burning; said master control including a rotating control motor capable of being placed in magnetic balance to stop movement thereof and of being magnetically unbalanced when energized 20 to cause movement thereof; a temperature responsive device for normally varying said control; and safety means for magnetically unbalancing said magnetic means when abnormal conditions of operation exist to thereby 25 stop normal operations of said apparatus.

2. In an oil burning apparatus, the combination of means for feeding, igniting and burning oil fuel; a master control for normally governing said feeding, igniting and 30 burning; said master control including means capable of being placed in magnetic balance to stop movement thereof and of being magnetically unbalanced to cause movement thereof; a temperature responsive device for normally varying said master control; safety means for magnetically unbalancing said magnetic means when abnormal 35 conditions of operation exist to thereby stop normal operations of said apparatus; and a 40 safety stop electrical contact to which a part of said control moves after operation of said safety means.

3. In an oil burning apparatus, the combination of means for feeding, igniting and 45 burning oil fuel; a master control for controlling said feeding, igniting and burning; said master control including an electromagnetic device being substantially magnetically balanced to prevent movement thereof and of 50 being magnetically unbalanced to create movement thereof; safety means responsive to abnormal conditions of fuel feeding and burning to cause said electromagnetic device to be unbalanced to thereby cause said apparatus to stop operations; a safety stop electrical contact to which an electrical conducting member of said control is moved after operation of said safety means; and a separately 55 operative device in said control adapted to vary said control to move said part from said safety stop contact to thereby replace the control for normal operation.

4. In an oil burning apparatus, the combination of means for feeding and igniting the 60 oil fuel, and means for operating said appa-

ratus; and an automatic electrical controlling means for governing said feeding, igniting and operating; said control means having included therein a control motor which has more than two brushes on its commutator and 70 each brush being electrically connected to part of said electrical control means to form predetermined electrical circuits under varying conditions of operation to normally give automatic operation of said burning apparatus and to stop said apparatus when abnormal conditions of fuel feed and burning exist, said motor having its field excited under all 75 conditions of operation of said apparatus.

5. In an oil burning apparatus, the combination of means for feeding and igniting the oil fuel, and means for operating said apparatus; and an automatic electrical controlling means for governing said feeding, igniting and operating; said control means having included 80 therein a control motor which has more than two brushes on its commutator and each brush being electrically connected to part of said electrical control means to form predetermined electrical circuits under varying 85 conditions of operation to normally give automatic operation of said burning apparatus, said motor having its field excited under all conditions of operation of said apparatus, and instantaneously acting safety 90 means connected in said automatic control and being responsive to conditions of combustion in said burner to vary the electrical control means to stop said apparatus.

6. In an oil burning apparatus, the combination of means for operating said apparatus, said means including the feeding of the fuel, and an automatic electrical control system for governing the operation of said apparatus, said control system including a control motor having three brushes each of which is electrically connected in said control system, an electrical distributor having two electrical conducting segments connected in said control system, and a movable arm 100 adapted to span said segments under predetermined operating conditions to vary the electrical control system, said movable arm being moved in response to movements of 105 said control motor.

7. In an oil burning apparatus, the combination of means for operating said burning apparatus, said means including the feeding and igniting of the fuel, and an automatic electrical control system for governing the 110 operation of said apparatus, said control system including a three-brush control motor, a distributing switching means electrically connected in said control means for varying the electrical connections in said control means under predetermined conditions and being driven by said control motor, a switch 115 in said control system operated by pressures developed by the existence of combustion in said apparatus for varying the electrical con- 120

- trol system to allow normal operation of said burning apparatus, and means in the control system for controlling the ignition, said ignition means being associated with said switch 5 and adapted to be rendered inoperative when said switch is moved in response to the existence of combustion in said apparatus.
8. In an oil burning apparatus, the combination of means for operating said apparatus, said means including the feeding and the igniting of the fuel, and an automatic electrical control system for governing the operation of said apparatus, said control system including a control motor having three 10 brushes each of which is connected in said control system, an electrical distributor having two electrical conducting segments connected in said control system, a movable arm adapted to span said segments under predetermined operating conditions to vary said electrical control system, said movable arm being moved in response to movements of said control motor, said motor having its field excited under all conditions of operation.
- 15 20 25 30 35 40 45 50 55 60 65 70 75 80 85 90 95 100 105 110 115 120 125
- of said apparatus, a switch operated by pressures developed by the existence of combustion in said apparatus, and being connected in said automatic control means to change the same upon being operated to allow continued operation of said burning apparatus, the ignition means being electrically associated with said switch and adapted to be rendered inoperative when said switch is moved in response to pressures developed by combustion.
9. In an oil burner apparatus, the combination of a burner, means for feeding fuel thereto, means for igniting the fuel, an electrical control system for governing the operation of said burner, a control motor connected in said control system, said control motor having two opposed windings adapted when energized separately to cause said control motor to rotate in opposite directions and when both are energized simultaneously to prevent the motor from rotating in either direction, means for energizing one of said windings to start said burner in operation, means for energizing the second winding after said oil has been ignited to prevent further rotation of said control motor and thereby allow normal burning operation of said apparatus to continue, said second winding adapted to return the operating parts of said apparatus to their normal positions after said first winding has been deenergized, said first winding adapted to continue the rotation of said control motor to a predetermined stop when said second winding is not energized thereby stopping the apparatus.
10. In an oil burner apparatus, the combination of a burner, means for feeding oil thereto, means for igniting the oil, an electrical control system for governing the operation of said burner, a three brush motor connected in said control system, a winding in
- said motor connected between two brushes for causing clockwise rotation thereof, a second winding in said motor connected between the third brush and one of the other brushes for causing said motor to rotate counter-clockwise, means in said control system for energizing one of said windings to start operations of said burner, and a second means also connected in said control system and operable upon accomplishing a predetermined burner condition for energizing said second winding while said first winding is energized to thereby cause said control motor to be substantially magnetically balanced and thus stop rotation thereof, said burner apparatus continuing normal operations while said control motor is thus balanced.
11. In an oil burner apparatus, the combination of a burner, means for feeding fuel thereto, means for igniting the same, an electrical control system for governing the operation of said burner, a three brush repulsion motor connected in said control system, a heat responsive means adapted to close the circuit between two of said brushes of said control motor when heat is required to thereby start the operation of said burner apparatus, a movable member associated with said burner and movable under pressures developed by combustion in said burner, and an electrical contact carried by said member and adapted when fuel is burning in said burner to close a circuit in said control system between the third brush and one of the other brushes thereby stopping the rotation of said control motor as the two circuits in said motor oppose each other, said burner continuing normal operations until one of said circuits is opened.
12. In an oil burner apparatus, the combination of a burner, means for feeding oil thereto, means for igniting the oil, an electrical control system for governing the operation of said burner, a three brush control motor connected in said control system, said control motor having a winding between two brushes which when energized causes said motor to rotate clockwise, a second winding between the third brush and one of the other brushes wound in opposition to said first winding for causing said motor to rotate counter-clockwise when energized, means for energizing the first winding to start the burner apparatus, means for also energizing the second winding when the fuel has been ignited, said two opposed windings thus energized causing said motor to stop its rotation, said second winding acting to return said control system to its normal non-operative position when said first winding has been deenergized, and means for maintaining said second winding energized until said control system has returned to its normal position.
13. In an oil burning apparatus, the com-

- bination of a burner, means for feeding fuel thereto, means for operating said burner, an electrical control means for governing the operation of said burner operating means, a control motor included in said control means, a distributor having two substantially annular electrical conducting segments connected to said control means, a distributor arm mounted to wipe over said segments in response to movements of said control motor to vary the electrical connections in said control means to allow continued operation of the burning apparatus under normal conditions and to stop the apparatus under abnormal conditions, and means responsive to pressure developed by combustion of said fuel in said burner to instantly stop the operation of said control motor and to thereby stop the movement of said arm over said segments thereby maintaining closed an electrical circuit which allows the burning apparatus to continue normally.
14. In an oil burning apparatus, the combination of a burner, means for feeding fuel thereto, means for operating said burner, an electrical control means for governing the operation of said burner operating means, a control motor included in said control means, a distributor having two substantially annular electrical conducting segments mounted concentric to each other and connected in said control means, one of said segments being of greater length than the other, a distributor arm mounted to engage the longer segment in normal stop position and to wipe over and contact with said segments in response to movements of said control motor to vary the electrical connections in said control means, and electrical means connected to said control motor and being operated by pressures developed by combustion of said fuel in said burner for changing the electrical balance of said control motor to cause the same to start or stop.
15. In an oil burning apparatus, the combination of a burner, means for feeding fuel thereto, means for operating said burner, an electrical control means for governing the operation of said burner operating means, a control motor connected in said control means, a distributor having two substantially annular electrical conducting segments, a distributor arm mounted to normally engage only one of said segments in normal stop position and to wipe over said segments in response to movements of said control motor to vary the circuits in said control means, means responsive to pressures developed by combustion of said fuel in said burner to govern the operation of said control motor to immediately stop the movement of said arm over said segments, and a temperature responsive means for governing the normal operation of said burning apparatus to cause the control motor to move said arm until combustion pressures operate to stop said motor and upon the next movement of said temperature responsive means to return said arm to normal position.
16. In an oil burning apparatus, the combination of a burner, means for feeding fuel thereto, means for operating said burner, an electrical control means for governing the operation of said operating means, a control motor connected in said electrical control, a distributor having two electrical conducting segments positioned beside each other and connected in said control means, one of said segments being longer than the other, a distributor arm mounted to wipe over said segments simultaneously in response to movements of said control motor, said arm being normally positioned in engagement with only one of said segments in normal stop position and adapted to engage both of said segments when set in motion by said control motor, and means responsive to pressures developed by combustion of fuel in said burner to vary the operation of said control motor to instantaneously stop the movement of said arm over said segments and to move said arm back to its normal position in contact with said longer segments after normal combustion has ceased.
17. In an oil burning apparatus, the combination of a burner, means for operating the same, an electrical control for governing said operating means, said control having a control motor included therein, a distributor connected in said electrical control and having two substantially annular segments mounted concentrically, one of said segments being longer than the other, a distributor arm for normally engaging only the longer segment when in normal stop position and adapted in its movement to wipe over said segments simultaneously, said arm being driven by said motor, a safety stop segment positioned to be engaged by said arm, a safety means instantly responsive to burner conditions and operating to vary the movements of said control motor and said arm to move said arm to said safety stop segment upon failure of ignition and when there is failure of combustion.
18. In an oil burning apparatus, the combination of a burner, means for operating the same, an electrical control for governing said operating means, said control having a control motor included therein, a distributor connected in said electrical control having two substantially annular segments mounted concentrically, one of said segments being longer than the other, a distributor arm engaging only the longer segment when said burner is not operating and adapted during its movement after starting of the burner to wipe over said segments simultaneously, said arm being driven by said motor, a safety stop segment positioned to be engaged by said arm under predetermined conditions, a safety

- means responsive to burner conditions and operating to vary the movements of said control motor to move said arm to said safety stop segment upon initial failure of ignition 5 and when there has been a failure of combustion, and separate operating means for operating said electrical control for causing said arm to be moved from said safety stop segment to normal stop position.
19. In an oil burning apparatus, a burner, means for feeding fuel thereto, a motor for operating said burner, a source of electrical supply for said motor, an enclosed switch for controlling the electrical supply to said burner motor, electrical control means for governing the operation of said burner motor, a three brush motor connected in said control means, a distributor mechanism also connected in said control means for varying the 15 electrical circuits therein, said distributor being mechanically connected with said three brush motor and driven thereby, means associated with said mechanical connection for opening and closing said enclosed switch in 20 the burner motor circuit, and a safety stop segment in said distributor mechanism to which a part of said mechanism is moved in response to abnormal burning conditions in 25 said burner causing said burner motor switch to open and said three brush motor to stop.
20. In an oil burning apparatus, the combination of a burner, means for feeding oil to said burner, a motor for operating said burner, an electrical control for governing the 30 operation of said burner motor, a three brush motor connected in said electrical control, a switching means mechanically driven by said three brush motor, an enclosed switch for opening and closing an electrical supply 35 to said burner motor, mechanical means associated with and operated by said three brush motor for operating said enclosed switch, a temperature responsive means for mainly controlling the operation of said three brush motor to thereby control the operations 40 of said burner, a safety stop segment in said switching means to which one part of said switching means is moved when there is initial failure of ignition and when there is 45 cessation of combustion in said burner, a switch operated by pressure resulting from the burning of said oil fuel, said switch adapted to close a circuit through said three brush motor to cause said motor and said 50 switching means to stop, and a safety means electrically connected to said three brush motor and being responsive to abnormal levels of said fuel for preventing the operation of said burner.
21. In an oil burning apparatus, the combination of a burner, means for feeding fuel thereto, means for operating said burner, electrical means for controlling said operating means, a control motor connected in said 55 electrical control and adapted to be mag-
- netically balanced to stop the rotation thereof under predetermined conditions, a switching mechanism, connected in said electrical control and adapted to be driven by said control motor, a movable arm included in said switching mechanism, a safety stop contact to which said arm is moved when abnormal conditions of operation exist in said burner, and means connected in said electrical control for selectively unbalancing magnetically said 70 control motor to cause said arm to be moved to its normal position or to said safety stop contact.
22. In an oil burning apparatus, the combination of a burner, means for feeding fuel thereto, means for operating said burner, electrical means for controlling said operating means, a control motor connected in said electrical control and adapted to be magnetically balanced to stop the rotation thereof under 75 predetermined conditions, a switching mechanism connected in said electrical control and adapted to be driven by said motor, a movable arm included in said mechanism, a safety stop contact adapted to be engaged by said arm under predetermined conditions, a temperature responsive means connected in said control and to said control motor, and a combustion responsive device connected in said 80 control and to said control motor, said control motor adapted to be started by the closing of said temperature responsive device and to be stopped by operation of said combustion responsive device and to thereafter be rotated in one direction by the opening of said 85 temperature responsive device and in the other direction by the opening of said combustion responsive device which causes said arm to be moved to said safety stop contact.
23. In an oil burning apparatus, a burner, means for feeding fuel thereto, means for operating said burner, electrical control means for governing said operating means, an electrical distributor connected in said 90 electrical control means, said distributor comprising an angular segment of approximately 320 degrees of a circle in length, a second segment of approximately 300 degrees of a circle in length and mounted concentric to said first segment, a safety stop electrical conducting 95 segment positioned between the ends of said first segment and insulated therefrom, a distributor arm normally positioned to engage said first segment in normal stop position, and means for moving said arm to wipe over 100 said first and second segments in a clockwise direction under certain conditions of burner operation and to move in a counter clockwise direction under other conditions of burner 105 operation and to be moved onto said safety stop segment when said fuel does not ignite 110 after said burner has been started.
- This specification signed this 13th day of May, 1925.
- ROBERT F. METCALFE.
